PIN CURL CLIP

Kenneth Reiner, 7875 Telegraph Road,
Pico-Rivera, Calif.

Filed June 16, 1958, Ser. No. 51,371

Term of patent 14 years

(Cl. D86—10)

FIG. 1

The essential features of my design are shown in full lines in the drawing.

I claim:

The ornamental design for a pin curl clip, as shown and described.
